UNITED STATES PATENT OFFICE.

FRED M. OEDER AND JAMES E. WRIGHT, OF WEST BAY CITY, MICHIGAN.

DESIGN FOR A SUGAR-BEET-THINNING SHOE FOR CULTIVATORS.

SPECIFICATION forming part of Design No. 30,849, dated May 23, 1899.

Application filed April 3, 1899. Serial No. 711,603. Term of patent 7 years.

To all whom it may concern:

Be it known that we, FRED M. OEDER and JAMES E. WRIGHT, citizens of the United States, residing at West Bay City, in the county of Bay and State of Michigan, have invented and produced a new and original Design for a Sugar-Beet-Thinning Shoe for Cultivators; and we do hereby declare the following to be a full, clear, and exact description of the same, reference being had to the accompanying drawings, forming a part thereof.

The drawings show a shoe for cultivators especially designed and adapted for use in thinning sugar-beets.

Figure 1 is a top view of the shoe. Fig. 2 is a side view. Fig. 3 is a front view. Fig. 4 is a view in perspective.

This design relates to the external form or configuration of a beet-thinning shoe, and is characterized by the contour and the relative arrangement of the surfaces comprising it when viewed in plan, front, and side elevations.

The shoe consists, as regards its configuration, of a side plane and a rearwardly-extending wing-plane. The side plane 1, the general contour of which is substantially that of a rhomboid with its upper and lower edges horizontal, inclines from the vertical at an

angle of about fifteen degrees when the shoe 30 rests in its normal position on a horizontal plane. A rectangular projection 2 extends vertically upward from the top edge of the plane 1. From the bottom diagonal edge of the rhomboid, which is at the rear of the 35 shoe, a triangular wing 3 extends diagonally downward under the slope of the plane 1, making an angle of about one hundred degrees therewith. The bottom edge of the wing 3 is in the same horizontal plane as the bottom edge of the rhomboid 1 and the traces of the two planes in the horizontal plane include an angle of about one hundred and forty degrees. The upper rear corner of the rhomboidal plane 1 is removed, as shown at 1^a in 40 Figs. 2 and 4, and the upper edge of the triangular wing 3 meets the line 1^a at its lower extremity.

What we claim is—

The design for a sugar-beet-thinning shoe 50 for cultivators herein shown and described.

In testimony whereof we affix our signatures in presence of two witnesses.

FRED M. OEDER.

JAMES E. WRIGHT.
